J. W. THOMAS

CIRCUIT CLOSER

Filed Jan. 19, 1921

By his Attorneys John W. Thomas
 Pennington, Davis, Marin & Edwards.

UNITED STATES PATENT OFFICE.

JOHN W. THOMAS, OF FULLERTON, PENNSYLVANIA, ASSIGNOR TO FULLER-LEHIGH COMPANY, A CORPORATION OF PENNSYLVANIA.

CIRCUIT CLOSER.

Application filed January 19, 1921. Serial No. 438,516.

To all whom it may concern:

Be it known that I, JOHN W. THOMAS, a citizen of the United States, residing at Fullerton, in the county of Lehigh, State of Pennsylvania, have invented certain new and useful Improvements in Circuit Closers; and I do hereby declare the following to be a full, clear, and exact description of the invention, such as will enable others skilled in the art to which it appertains to make and use the same.

The present invention relates to circuit closing devices adapted for use in conjunction with containers, more especially a tank or bin for liquids or finely divided solids such as pulverized coal, to control the filling of the container and to indicate as well when the bin is empty, as the intermediate progressive levels of the material during the filling and emptying of the bin.

The invention comprehends as one of its parts the combination with a bin provided with means for feeding material thereto, of a device responsive to the pressure of the material in the bin for controlling the feeding means. When the material being fed to the bin reaches a predetermined height fixed by the position of the device in the bin, which would ordinarily be close to the top opening thereof, the device operates through the pressure of the material on its parts to automatically shut off the feeding of material, thus precluding the overflow of the bin. This might easily occur where for instance a signalling device which is depended upon to give warning to an operator to shut off the material when the bin is full, is unheeded. The means for feeding material to the bin may consist of power operated mechanism, preferably motor driven, in which case the device responds to the pressure of the material in the bin to start and stop the feeding mechanism, as by starting and stopping the motor. Irrespective of the means for driving the feeding mechanism, but preferably in accordance with an arrangement whereby a motor is employed for this purpose, such mechanism embodies a hopper and a screw conveyor. In the specific embodiment of the invention hereinafter described the motor for driving the screw conveyor is in circuit with an overload circuit breaker and the controlling device, located near the upper end of the bin, operates the circuit breaker

to stop the motor and the feeding of material by the screw conveyor when the bin is full.

For whatever purpose the device may be used, as, for instance, to shut off the means for feeding material to a bin when the bin is full, or for the purpose of indicating the progressive heights reached by the material during the filling and emptying of the bin, the device comprises a pair of diaphragms, preferably flexible, which are both exposed to the same pressure, the variations in which, from a selected normal, cause the device to operate. Associated with the device may be an electric circuit which is controlled by the movements of the diaphragms, and the device may embody circuit-controlling means which are operated by the diaphragms to open the circuit when the diaphragms are subjected to a pressure in excess of the selected normal. In any event, however, the diaphragms are caused to have a relative movement, due to variations in pressure from the selected normal, and the circuit-controlling means, which may conveniently take the form of a pair of contacts, one associated with each of the diaphragms, may also be arranged to be given a relative movement, upon the relative movement of the diaphragms. Each diaphragm is preferably provided at its center with a stiffening member which serves to reinforce and protect the diaphragm and also to provide a means by which the circuit controller may be actuated. In one form of the device I make use of a pair of diaphragms which are mounted on opposite sides of a housing in the form of a ring which is intended to be placed within the bin or other container so that both diaphragms are exposed to the pressure of the material within the bin. In the space between the diaphragms is a circuit-controlling device, which may take the form of a pair of contact members. These contact members may be carried by the diaphragms, although I prefer to mount each contact member upon the free end of a flexible arm, the other end of which is anchored at any suitable point within the housing. These flexible arms are connected intermediate their ends with the stiffening members, and as the diaphragms move the arms are caused to flex so as to produce a relative movement of the contact members either of

separation or approach. In the preferred embodiment of the invention I make use of a pair of flexible diaphragms and a pair of flexible arms, each of which carries a contact. These arms are so arranged that as the diaphragms are moved toward each other by pressure variations in excess of the selected value, the contact members are caused to separate. These contacts in turn form part of an electric circuit which is arranged with suitable indicating and other devices so that a signal may be given, or, if desired, a piece of machinery, as, for instance, the motor associated with the feeding mechanism, may be shut off. The diaphragms are mounted in spaced relation in the housing, and the contact members on their arms are placed between them. Both diaphragms are thus exposed to the pressure, the variations in which cause the device to operate, and both contact members are given a simultaneous movement as the diaphragms are moved.

In another form of the device I make use of a single diaphragm exposed to the pressure. This diaphragm is provided with a stiffener, and the flexible arm having one free end on which is mounted a contact, is secured to the stiffener intermediate its ends. A second contact member adapted to cooperate with the first is supported within the housing on which the diaphragm is mounted, and as the diaphragm is moved by pressure variations, the contacts are caused to move relatively to each other so as to open or close a circuit, as the case may be.

The device is capable for use in indicating the progressive heights which are reached by the material as the bin is being filled, as, for instance, by causing the contact members to control a circuit which lights a lamp when the pressure of the material on the diaphragms causes the contacts either to separate or come together, but the device is also capable of use for indicating when the bin is empty. In this adaptation of the invention the diaphragm or diaphragms may be arranged so that upon the release of pressure caused by the level of the material falling below that at which the device is located the contact members will either move together or apart in such a way as to establish or break a circuit which may, in turn, operate a signal or some other piece of apparatus.

The different parts of the present invention described in the foregoing may be variously employed conjunctively to produce for example, the combination with a bin provided with means for feeding material thereto, of a device responsive to the pressure of the material in the bin for controlling said feeding means, and means for indicating the progressive filling and emptying of the bin; or as in the preferred con-

struction described hereinafter also including means for indicating when the bin is empty.

In the drawings, Fig. 1 is a view of a pressure responsive element provided with two diaphragms; Fig. 2 is a modified pressure responsive element provided with one diaphragm; and Fig. 3 shows a modified mounting for one of the pressure responsive elements.

Referring now to the drawings, 1 indicates an annular ring provided with a pair of circumferential flanges 2 to which are respectively attached flexible diaphragms 3 made of rubber, leather, or the like. Stiffening discs 4 are suitably mounted on the central part of the diaphragms. A pair of angled resilient arms 5 attached to the ring 1 are also attached, as indicated at 6, to the stiffening discs 4 and are then bent, as indicated at 7 and 8, to provide a mounting for the carbon contact pieces 9. One of these spring arms 5 is made in two parts, the two ends being insulated from each other by the insulating block 10, in which its ends are mounted. The stiffening discs 4 are an important adjunct of the invention. They serve to both mount the resilient arms 5 in operative relation with the diaphragms and to prevent the carbon contact pieces and associated parts from contacting with and puncturing the adjacent diaphragm, when the diaphragms are pressed toward one another. The current is led to the contact blocks 9 through the wires 12.

The pressure responsive element is placed on the inside of the bin, so that the material in the bin will press against both diaphragms. A bracket for so mounting it may be attached to the lower part of the ring 1 as indicated at 13. It is evident that pressure of the material in the bin will cause the circuit to be broken, which operation will operate a suitable signal as will be described.

Referring now to Fig. 2, a modification is shown in which but a single diaphragm, indicated at 14, is used. This diaphragm is mounted upon a suitable casing 15, which is flanged as indicated at 16, for mounting in a suitable aperture in the bin 17. Otherwise the structure and operation of this modification are very similar to that of Fig. 1, the corresponding parts being similarly numbered.

Referring now to Fig. 3, the bin 17 is shown as filled with liquid or finely divided solid, such as pulverized coal, for example, to the height indicated at 18. A plurality of pressure responsive devices, of the kind shown in Fig. 1, are mounted at various levels in the bin 17, such devices being indicated generally at 19 and 20. Each of these pressure responsive devices controls an electric circuit 22 in which signals, such as the

lamps 23, are located. It will be apparent that when the material in the bins is in contact with one of these indicators 19 or 20 the lamps will be dark, and that when the material falls below these devices the lamps will be lighted. The lighting and extinguishing of these lamps will therefore give both an indication of the level of the material in the bin as well as an indication of the rate at 5 which it is being filled or emptied.

At the bottom of the bin is located a signal for indicating when the bin is empty. In its preferred form this device comprises a pressure responsive circuit closing device 24, 15 comprising spring arms designed to be brought into contact by pressure of the material in the bin against them. This device is in circuit with a relay 25, the relay in turn controlling both the bell 26 and the 20 lamps 27. When the material in the bin falls below the pressure responsive device 24, the circuit is broken and the bell 26 and the lamps 27 will be operated to give an alarm that the bin is empty. The lamps 27 25 are normally extinguished.

Near the top of the bin is located a pressure responsive device 28 similar to 19 and 20, this device, however, controlling a relay 29 as well as the usual signalling lamps 23. 30 The relay 29 controls an audible signal such as the bell 30. It will be apparent that when the material in the bin reaches the level of the element 28 the circuit will be broken by 28, whereupon the relay 29 will close the 35 circuit to the bell 30 to give an alarm that the bin is filled.

At the top of the bin is a pressure responsive element 32, similar to 19 and 20, this element controlling the circuit 33, in which 40 is located the overload circuit breaker, 34. This circuit breaker controls the circuit 35 through the motor 36, which operates any desired form of mechanism for feeding material to the bin, here shown as a screw 45 conveyor 37. When the material reaches the level of the pressure responsive device 32, the motor 36 will be disconnected so as to stop further filling of the bin.

When the bin is nearly empty the lights 50 27 will be lighted and the bell 26 will be rung to indicate that fact. As the bin fills, these signals will be disconnected and the lights 23, placed at various levels, will be successively extinguished as the material in 55 the bin attains successive levels. When the material in the bin reaches the level of the pressure responsive element 28 an alarm bell 30 will be rung. Any overflow of the bin is 60 prevented by the pressure responsive device 32 which throws out the filling mechanism 36 and 37 when the material in the bin reaches the top.

The modification shown in Fig. 3 shows the contact carbons 9 and their associated 65 arms mounted in a detachable glass casing,

which projects outside of the bin, so that the parts may be readily repaired and inspected. The glass casing indicated at 40 is carried by the mounting ring 41 held in a suitable aperture in the wall of the bin 17. 70 A pressure responsive diaphragm 14 is mounted in the inner side of the mounting 41, so as to be subjected to pressure of the liquid or finely divided solid in the bin. 75

I claim:

1. A circuit closer actuated by variations in pressure comprising the combination of a pair of diaphragms placed face to face and exposed to the same actuating pressure these diaphragms being arranged to be given a simultaneous relative movement by variations in the pressure from a selected value, and a contact member associated with each diaphragm and movable thereby, these contact members being disposed between the diaphragms and being arranged to cooperate and to be given a relative movement of separation when the diaphragms are subjected to a pressure in excess of the normal value. 80

2. A circuit closer actuated by variations in pressure comprising the combination of a pair of flexible diaphragms directly exposed to the same actuating pressure, each of these diaphragms being movable toward the other when the pressure exceeds a selected value, 95 and a contact member associated with each diaphragm, these contact members being placed between the diaphragms and being arranged to cooperate and to be moved apart 100 when the diaphragms move toward each other.

3. In a circuit closer actuated by variations in pressure, the combination of a flexible diaphragm exposed to the pressure and provided with a stiffener, a resilient arm anchored at one end and carrying a contact member on its free end, the said arm being secured to the stiffener intermediate its ends and being adapted to be flexed by the diaphragm as the latter is moved by pressure variations, and a second contact member arranged to cooperate with the first. 110

4. A circuit closer actuated by variations in pressure comprising the combination of a housing, a pair of flexible diaphragms secured to the housing and adapted to be exposed to the actuating pressure, these diaphragms being relatively movable according to pressure variations, a stiffener on each diaphragm, a pair of resilient arms, each arm being associated with a diaphragm and secured at one end to the housing, each arm being secured intermediate its ends to one of the stiffeners, and contact members mounted on the free ends of the arms and arranged to cooperate. 115

5. A circuit closer actuated by variations in pressure comprising the combination of a pair of diaphragms exposed to the actuat- 120 125 130

ing pressure and movable toward each other when the pressure exceeds a selected value, stiffeners on the diaphragms, an arm associated with each diaphragm, this arm being anchored at one end and being secured to the stiffener intermediate its ends, and contact members carried on the free ends of

the arms, the arms and contact members being so arranged as to cause the contact members to be separated when the diaphragms are moved toward each other by pressure in excess of the selected value. ¹⁰

In testimony whereof I affix my signature.
JOHN W. THOMAS.
